(57) CLAIM

The ornamental design for a table, as shown and described.

DESCRIPTION

FIG. 1 is a perspective view of my table;

FIG. 2 is a front view, the back view (not shown) is a mirror image thereof;

FIG. 3 is a right side view, the left side (not shown) is a mirror image thereof; and,

FIG. 4 is a top view of my table.

The broken lines are for environmental purposes only and form no part of the claimed design.

1 Claim, 4 Drawing Sheets# US D605,432 S
